COLORADO.

MEANS FOR OPERATING DOORS.

1,095,544.

Specification of Letters Patent.

Patented May 5, 1914.

Application filed October 23, 1912. Serial No. 727,367.

To all whom it may concern:

Be it known that we, GEORGE W. BASHAW, WILLIAM O. COOK, and PAUL C. WITHROW, citizens of the United States, and residents of Denver, in the county of Denver and State of Colorado, have invented new and useful Improvements for Means for Operating Doors, of which the following is a description, reference being had to the accompanying drawings, which form a part of our specification.

Our invention relates to means for operating doors, more especially intended for use in connection with the doors of a locomotive fire-box.

The object of the invention is the provision of means adapted to be manually operated, in connection with two portions or door-sections adapted to move in vertical directions, the one above the other, and in the particular constructions shown, arranged to move substantially parallel with the wall of the fire-box; the means being such that the doors may be easily and quickly operated and whereby the doors will automatically move to closed position without, however, allowing them to have a material striking or jarring force when coming together.

A further object of the invention is the provision of a construction wherein the oppositely moving door-sections will be substantially in balance when the doors are in closed position; a leverage being obtained whereby the desired power is had to easily start the door-sections from a state of rest, without requiring great or increasing exertion on the part of the operator and at the same time providing a construction wherein little foot travel or movement on the part of the operator is necessary, thus obviating the necessity of the operator lifting his entire foot from the deck of the engine, and wherein the doors and operating means will be shifted to an unbalanced position so as to induce the automatic and quick closing of the doors as soon as the mechanism is released by the operator, as will more fully appear from the following detailed description.

In the drawings:—Figure 1 shows one form of our invention in elevation as the same would be applied to the front wall of

the fire-box of an engine, with portions broken away in order to show the exact construction of the cam mechanism employed. Fig. 2 is a side elevation of the invention applied to the front wall of a fire-box; the water-jacket of the fire-box being shown in vertical section. Fig. 3 is a modified form of our invention. Fig. 4 is a side elevation thereof showing the water-jacket, in proximity to the fuel receiving-opening of the fire-box, in vertical section.

In the exemplification of our invention, as illustrated in Figs. 1 and 2, the invention is shown applied to a diagonally split door forming two door-sections which are pivotally secured so as to swing vertically and in opposite directions; each section being adapted to cover half of the fuel introducing opening of the fire-box, as is evident from the construction shown and hereinafter described. The fuel opening is provided with a suitable frame or ring as shown at 5, which is properly secured to the wall of the fire-box in any suitable manner. The ring or frame 5 is shown provided with the tangentially extending brackets or members 6 and 7, to which are pivotally secured the upper door-section 8 and the lower door-section 9, respectively; the upper door-section 8 being fulcrumed at 10 while the lower door-section is fulcrumed at the point 11. The door-sections are made of any suitable design, and the ring or frame 5 is also provided at points in proximity to the free ends of the door-sections with suitable lugs or brackets 12, 12, which are adapted to hold the free ends of the doors against the ring or frame and secure the doors against the action of any exploding gases. The pivotal points 10 and 11 of the two door-sections are fixed at predetermined points above and below the center of the fire-box opening or hole to permit of the desired opening of each member; and in the particular construction illustrated, the door is so split that when in open position the abutting edges of the sections will come into substantially the same horizontal planes of the respective fulcrum points.

The ring or frame 5 is also provided with a vertically extended member or bracket 13, the upper end whereof is provided with a horizontally extending portion having a socket or bearing point which receives a cam

14 formed integral with equalizing lever or bar 15. One end of lever or bar 15 has a link 16 pivotally connected thereto; the lower end of link 16 being preferably bifurcated, as more clearly shown in Fig. 2, which 5 bifurcated end is pivotally secured at 17 to the upper door-member 8. The opposite end of equalizing bar or lever 15 is provided with a rod or bar 18 pivotally connected thereto, the lower end of rod or bar 18 being provided with a cam 19 at its lower extremity, either formed integral therewith or properly secured thereto, the cam being adapted to extend into a cam-socket 20 10 formed in the under side of the lower door-section 9, or more properly speaking in the under surface of the pivot-receiving arm or extension of the lower door-section as clearly shown in Fig. 1. The cam socket 20 is preferably formed of increasing depth, the depth 15 increasing toward the side of the socket farthest removed from the pivotal point 11 of the door-section; while the cam 19 is preferably provided with a sloping or somewhat arcuated surface as clearly shown, thus 20 providing clearance or space between the upper surface of the cam and the socket at the end of the socket farthest removed from the pivotal point 11 when the door-sections 25 are in normal or closed position. The socket 20 is provided with a depression which receives the heel or projection 19^a formed on the cam whereby any slipping action of the cam against the door is prevented.

25 The two door-sections may be symmetrical and made from the same pattern; for that reason the upper door-section 8 is shown provided with a cam-socket shown in dotted lines at 21 similar to cam-socket 20 in the lower door-section; the socket in the upper door-section, however, performs no function but permits the door-sections being assembled without regard to their position.

30 The lower side of the pivot receiving arm or projection of upper door-section 8 is provided with a cam-socket at 22, which is made of increasing depth as it approaches the pivotal point 10.

35 The ring or frame 5 is shown provided with a bracket 23 and pin 26 whereby the vertically movable push rod or member 24 is slidably held in place; the push rod or member 24 being provided with a slot as at 25 through which the stud or pin 26 extends. The lower end of the push rod 24 is pivotally connected at 27 with the inner or short arm 28 of foot treadle or lever 29; the treadle 29 being pivotally mounted at 30 on a suitable bracket 31 which latter may be 40 properly secured to the boiler-head.

45 The push rod or member 24 is provided at its upper end with a cam 32 which extends into cam socket 22, as clearly shown in Fig. 1; the end of the cam in contact with door-section 8 when the latter is in normal or

closed position, is preferably provided with the protrusion or heel 33 which extends into a depression formed in door member 8 whereby slipping of the cam on the door member is prevented.

50 Where the downward movement of door-section 9 is not restricted by reason of the proximity of the engine deck to the fire-box opening, or for any other reason, the two door-sections are made symmetrical, with the distance between the points 10 and 17 on the upper door-section equal to the distance between the pivotal point 11 and the point 34 on the lower door-section, while the distance between the point 35 and contact point 36 on the equalizer bar 15 is slightly greater than the distance between the point 36 and the point 37. The purpose in having the distance between the points 35 and 36 slightly greater than the distance between the points 36 and 37, is to prevent the tendency of the doors to work themselves open; the door-sections together with their respective connections being very nearly balanced when in closed position.

55 Where the movement of the lower door-section is restricted in any way, the lower door-section is made narrower and relatively heavier than the upper door-section so as to compensate for the difference in dimensions, and the points 17 and 34 are spotted or moved the required distance from the fulcrum points 10 and 11, respectively, so as to impart a relatively greater travel to the upper door-section than that had by the 60 lower door-section.

65 In the operation of the construction shown in Figs. 1 and 2, the depression of foot treadle or lever 29 will move push rod or member 24 upward, and force upper door-section 8 upward about its pivotal point 10. The upward movement of door-section 8 will move link 16 with it, thereby rocking equalizer bar 15 on the member or bracket 13 so as to allow rod or bar 18 to move downward, which in turn permits door-section 9 to drop or swing downward about its pivotal point 11.

70 In the operation of the door-sections as just described, the cam 32 will have a rolling or shifting contact with upper door-section 8 so that the side or surface of the cam nearest pivotal point 10 will be in contact with the lower surface of the door-section when the door has been completely 75 opened. By reason of this rolling or shifting contact between the cam of push rod 24 and the upper door-section, very little travel on the part of push rod 24 is necessary and, therefore, but slight downward movement 80 on the part of foot treadle is required. During the opening operation of the doors, the distance between points 35 and 36 has increased and moved toward the right in Fig. 1, so as to be at the extreme right hand corner 85

ner of cam portion 14, while the distance between pivotal point 11 of the lower door-section and point 34 on the cam 19 has increased and moved toward the outer or left hand corner of cam 19, in Fig. 1. The shifting of the cam portions in the manner just described provides a differential leverage in favor of the upper door-section, so that when the door-sections have been moved to a complete open position, the upper door-section together with its connected rods and levers will overbalance the lower door-section and induce the automatic closing of the door-sections as soon as the operator releases foot treadle 29.

With the door-sections and their respective connections very nearly in balance while in closed position, it is evident that they may be easily started from a state of rest without requiring a great exertion on the part of the operator, which would be the case if the upper door-section greatly overbalanced the lower door-section while the sections are in closed position. Sudden foot pressure on the treadle will give the door-sections an initial velocity sufficient to carry them to an entirely open position without any increased effort on the part of the operator, and by reason of the shifting or rolling contact between the cam end of the push rod and the upper door-section, it necessitates but slight movement being given to the foot treadle in order to induce a complete opening of the door-sections. By reason of the small movement necessary to completely open the door, it is evident that the foot treadle may be so placed that the operator need merely raise his toe or heel without lifting his entire foot from the engine deck when desiring to operate the doors. The small amount of power required to operate or open the door-sections, as well as the small or short travel of the foot treadle necessary to accomplish a complete opening of the door-sections, is the great desideratum of a successful device of the character herein described, being essential both from the standpoint of the constant energy necessary on the part of the fireman as well as regards his safety in being able to keep his foot on the engine deck and, therefore, better able to maintain his balance during the running of the locomotive.

In Figs. 3 and 4, we illustrate a modified form of our invention, wherein the door comprises the two sections 8^a and 9^a adapted to slide vertically in the guide members 38 and 39. In this construction the frame or ring 5^a is provided with a depending bracket 40, the lower end whereof has a horizontally extending portion to provide a bearing point or socket as shown at 41 in Fig. 4. The upper door-section 8^a has a link 42 pivotally connected thereto; pivotally connected to the upper end of link 42 at the point 43

is a lever 44, the outer end whereof is fulcrumed or pivotally connected at 45 to an extension or bracket 46 preferably formed integral with guide member 38. The lower door-section 9^a has a similar link 47 pivoted thereto; the lower end of the link being pivoted at 48 to a lever 49, the latter being pivoted or fulcrumed at 50 to a bracket or extension 51 which is preferably secured to or formed integral with guide member 39.

A vertically movable push rod or member 52 is shown provided with a link 53, see Fig. 4, which may be secured to lugs formed near the lower end of rod 52, and link 53 is pivotally secured to a lever 54 which is fulcrumed at 55 to a bracket 56, which latter may be suitably secured to guide 38 or to the wall of the fire-box. The other end of lever 54 is pivotally secured to foot treadle or lever 57 which has its fulcrum at the point 58 which may be formed by providing the inner end of the treadle with a lug or hook portion taking to the rear of the lower end of guide member 38, so that pressure by the operator on the treadle will compel the treadle or foot lever to move about the point 58 thereby drawing the short arm of lever 54 downward and move the long arm thereof upward, whereby link 53, together with push rod 52, will be moved upward and compel lever 44 to move upward therewith.

Pivotally secured to the lower part of push rod 52 is an equalizing bar or lever 15^a, which is provided with a cam portion 14^a which has bearing in the depending bracket 40 of the frame or ring 5^a. The cam portion 14^a is provided with a sloping or somewhat arcuated surface, as clearly shown in Fig. 3, so that one portion of the cam, namely the portion toward the side on which push rod 52 is located, is normally in contact with the surface of the bracket, thus providing clearance or space between the opposite side or end of the cam and the surface of the bracket, as clearly shown in the figure.

In order to prevent any slipping of the cam on the bracket, the cam may be provided with a heel or depending portion 59 extending into a similarly formed depression in the bracket.

The opposite end of equalizing bar or lever 15^a is pivotally connected to a link 60, which link in turn is pivotally connected at the point 61 to lever 49, of lower door-section 9^a.

The upper end of push rod 52 is shown provided with a slotted end 52^a which receives a stud or pin 62 whereby the upper end of the push rod may be slidably held in place and the weight of the push rod and its connections are suspended from lever 44 when the operator releases foot treadle 57 after the door-sections have been moved to open position. The guide member 39 is also shown provided with a suitable pawl 130

63 so located that it may engage in the socket 64, with which upper door-section 8^a is provided, after the door-sections have been moved to open position, thus permitting the door to be held open when it is desired to have access to the fire-box for cleaning or other purposes.

In practice the door-sections and their respective connections are so formed that they will be substantially in balance while the door-sections are in closed position. With these conditions the operator need not use great exertion to operate the construction, as the door-sections may be easily started in motion from a state of rest; the sudden foot pressure applied to the treadle will give sufficient initial velocity to carry the sections to complete open position without requiring any increased effort. A depression of foot lever 57 will draw the short arm of lever 54 downward, move the long arm thereof upward, as well as link 53, whereby push rod 52 is operated in a similar direction. The cam portion of push rod 52 farthest removed from fulcrum point 45 will move lever 44 upward. By reason of the construction, great leverage is obtained at the initial point of operation, namely at the time when the greatest power is necessary and which can be obtained without much exertion; but during the upward movement of door-section 8^a together with its lever 44, the cam portion nearest pivotal point 45 will be brought into contact with the lever 44. This construction obviates the necessity for any considerable upward movement on the part of the push rod 52, and consequently requires but slight downward movement on the part of foot treadle, thereby enabling the toe or heel of the operator simply to be employed in the opening operation without requiring the operator to lift his foot from the deck of the engine. When the upper door-section 8^a is moved upward to open position, equalizing bar or lever 15^a will rock on the cam portion 14^a so that the end of equalizing bar 15^a connected to link 60 will move downward and with it lever 49, thus allowing lower door-section 9^a to drop.

With the door-sections moved to complete open position, an overbalanced condition is secured in favor of the upper door-section and its connections, sufficient to cause the automatic closing of the door sections as soon as the operator lifts his foot from treadle 57; it being induced by the differential leverage obtained in the shifting of the fulcrum point of cam 14^a, which shifting provides a long arm intermediate of push rod 52 and the portion of cam 14^a nearest link 60.

Where the downward movement of lower door-section or member 9^a is limited for any reason, the spotting or placing of the points

61 and 62 must be altered so as to induce greater relative movement on the part of upper door-section 8^a.

By employing the connection between the inner ends of levers 44 and 49 and the respective door-sections 8^a and 9^a shown and described, and locating the fulcrum points 45 and 50 on a horizontal line approximately halfway between the open and closed positions of the points 43 and 48 respectively, the pulling action of the levers will be exerted as near the vertical axes of the sections throughout the travel of the sections as possible, thereby preventing any tendency of the doors sticking or wedging themselves during operation.

In this construction the push-rod or member 52, in addition to the function of raising or opening the upper door-section, also acts as a connecting link intermediate of the lever connected to the upper door-section and the equalizing lever or bar; in this respect the push rod or member takes the place of link 16 of the construction shown in Figs. 1 and 2.

We have shown and described specific forms of our invention wherein a substantial balanced condition is had while the door-sections are closed, and wherein an unbalanced condition is obtained after the door-sections have been moved to open position, together with a differential leverage, sufficient to overcome any friction of the working parts as well as that caused by the pull of the fire draft, so that automatic closing of the door-sections is induced. The constructions, however, may be somewhat varied in certain details without, however, departing from the spirit of our invention, and we do not wish, therefore, to be understood as limiting ourselves to the exact constructions shown and described.

What we claim is:-

1. Means for operating doors, comprising a pair of door-sections arranged to move in opposite directions, each section being controlled by a fixed fulcrum point, a pair of members having operative relation with said door-sections, an equalizing member having operative relation with said pair of members and provided with a fulcrum point intermediate of its ends adapted to shift during movement of the door sections, and vertically movable means adapted to move the upper door-section upward and rock the equalizing member so as to shift its fulcrum or contact point relative to the ends thereof and allow the lower door-section to move to open position thereby inducing an unbalanced condition in favor of the upper door section, the engaging surface of said vertically movable means being arranged to shift or move toward the fixed fulcrum point controlling the upper door-section during the opening operation of the door-sections.

2. Means of the class described, comprising a pair of oppositely movable door-sections; a vertically movable member adapted to transmit upward pressure to the upper door-section, and transversely arranged means operatively connected with both door-sections whereby the two door-sections are made to move together, said means being provided with a bearing point intermediate of its ends adapted to shift relative to the vertical plane through which the door-sections move when the latter are separated and thereby produce an overbalanced condition in favor of the upper door-section so that the automatic closing of the sections is induced.
3. Means for operating doors, comprising a pair of door-sections arranged to move in opposite directions, a pair of members having operative connection with both door-sections, a rocking member operatively connected with both door-sections and provided with a fulcrum point intermediate of its ends adapted to shift relative to the ends thereof during the operation of said door-sections whereby an unbalanced relation is induced and simultaneous operation of the door-sections obtained, and means whereby movement of the door-sections to open position is induced.
4. Means of the class described, comprising a pair of door-sections fulcrumed so as to move in opposite vertical directions, means intermediate of said sections and provided with a fulcrum point intermediate of the ends thereof adapted to shift whereby the simultaneous operation of the two sections is produced and the automatic closure of the sections secured through the shifting movement of said fulcrum point toward one end of said means, and means for causing the opening of the door-sections, the power-exerting point of said last-mentioned means being adapted to shift or move toward and away from the fulcrum controlling one of said door-sections during the opening and closing, respectively, of the door-sections.
5. Means of the class described, comprising a pair of door-sections adapted to move in opposite vertical directions, means whereby pressure on the upper section may be had, the point of application of the pressure being arranged to shift or move in a transverse direction, and means having positive operative relation with both sections whereby the simultaneous operation of the sections is produced, said means being arranged transversely of the door-sections and provided with an intermediate shifting fulcrum point whereby an unbalanced condition is obtained in favor of the upper door-section when the doors are open and the automatic closing of the sections induced thereby.
6. Means of the class described, comprising a pair of door-sections arranged to move vertically in opposite directions, each section being controlled by a fulcrum point arranged at the side of the vertical plane in which said sections move, a vertically movable member whereby an upward pressure is transmitted to the upper door-section, said member having shifting movement relative to the fulcrum point which controls the upper door-section, and a tiltably mounted member whereby both door-sections are made to move together, said member being provided with a fulcrum point intermediate of its ends, so arranged as to shift relative to the ends of the member whereby an overbalanced relation between the sections in favor of the upper door-section is produced and the automatic closure of the sections obtained.
7. Means of the class described, comprising a pair of door-sections fulcrumed so as to move in opposite vertical directions, the fulcrum points of the sections being arranged beyond the vertical plane through which the sections move, a vertically movable member adapted to transmit upward pressure to the upper door-section in proximity to the fulcrum point of said section, the pressure exerting point of said member being arranged to move toward and away from said fulcrum point during the movement of the sections, and a transversely arranged tiltably mounted member having an intermediate fulcrum point arranged to shift relative to the ends of the member, the opposite ends of the member having controlling relation with the opposite door-sections, so that tilting of said member will produce an overbalanced condition in favor of the upper door-section and induce the automatic closure of the sections.
8. Means of the class described, comprising a pair of vertically movable door-sections, said sections being substantially in balance while in closed position and arranged to move in opposite directions, a vertically movable member having controlling relation with the upper door-section, means whereby said member is moved upward, and a tiltably mounted member arranged transversely with its opposite ends placed in controlling relation with opposite door-sections, said last-mentioned member having a shifting fulcrum point intermediate of its ends whereby an unbalanced condition of the member is produced in favor of the door-section occupying the higher horizontal plane when the door-sections are separated and an over-balanced relation between the door-sections established, which will induce the automatic closing of the door-sections.
9. Means of the class described, comprising a pair of door-sections arranged to move in opposite vertical directions, each section being controlled by a fulcrum point, the

fulcrum points of the two sections being arranged on opposite sides of the vertical plane through which the sections move, a vertically movable member whereby upward pressure is transmitted to the upper door-section, said member having shifting movement relative to the fulcrum point which controls said upper door-section, and a tiltably mounted member arranged intermediate of the vertical planes of the fulcrum points of said sections whereby both door-sections are made to move together, said member having a bearing or fulcrum point arranged intermediate of the vertical planes of the fulcrum points of the door-sections, adapted to shift relative to said vertical planes whereby an overbalanced relation between the sections in favor of the upper door-section is produced when the doors are open and the automatic closure of the sections obtained.

10. In means of the class described, the combination of a frame member provided with an extended portion or bracket, with a pair of door-sections arranged to move vertically in opposite directions, each section being controlled by a fulcrum point

arranged on opposite sides of the vertical plane through which the sections move, a vertically movable member adapted to transmit upward pressure to the upper door-section, said member having shifting movement relative to the fulcrum point controlling the upper door-section, and a transversely arranged tiltably mounted member whereby both door-sections are made to move together, said tiltably mounted member having a bearing or fulcrum point on said extended portion or bracket of the frame member, arranged to shift relative to the vertical planes occupied by the fulcrum points of the sections whereby an overbalanced relation between the sections in favor of the upper door-section is produced when the doors are opened and the automatic closure of the sections obtained.
